(57) CLAIM

The ornamental design for a car body, as shown and described.

DESCRIPTION

FIG. 1 is a front elevational view of a car body showing our new design;

FIG. 2 is a right side elevational view thereof;

FIG. 3 is a left, front perspective view thereof;

FIG. 4 is a right, rear perspective view thereof;

FIG. 5 is a rear elevational view thereof;

FIG. 6 is a left side elevational view thereof; and,

FIG. 7 is a top plan view thereof.

The broken lines shown in the drawings are for illustrative purposes only and form no part of the claimed design.
